UNITED STATES PATENT OFFICE.

CARL A. BROWN, OF TOLEDO, OHIO, ASSIGNOR TO GENERAL ELECTRIC COMPANY,
A CORPORATION OF NEW YORK.

MACHINE FOR CUTTING GLASS.

Application filed November 4, 1919. Serial No. 335,720.

To all whom it may concern:

Be it known that I, CARL A. BROWN, a citizen of the United States, residing at Toledo, in the county of Lucas, State of Ohio, have 5 invented certain new and useful Improvements in Machines for Cutting Glass, of which the following is a specification.

My invention relates to machines for cutting glass and more particularly to machines 10 for "cracking-off" the surplus neck of incandescent lamp bulbs and similar articles.

Incandescent lamp bulbs made by automatic machines, especially those made from glass tubing, usually have a neck of excess 15 length which must be cut off before the lamp can be used. Heretofore, removing the excess neck has been accomplished by scoring the glass on a file or similar instrument and cracking the glass off on the scored line. 20 This is a comparatively slow and expensive process as it is done by hand and furthermore the length of neck remaining on the bulb varies through a comparatively large range.

According to the method and apparatus 25 of my invention, the bulbs are inserted in a rotatable carrier which brings the neck of the bulb successively into the several operative positions. First, the neck is locally heated on the line at which it is to be cracked-off and the neck is cut and chilled on this line. The excess neck is then knocked off. The bulb is automatically removed 30 from the rotatable carrier and deposited in a suitable container. Among the advantages of my invention may be mentioned, 35 uniformity of the length of neck, speed of operation, reliability of results and decreased breakage.

In the accompanying drawing, Fig. 1 is 40 a top plan view of a machine made according to my invention; Fig. 2 is a side elevation of the same showing the driving means; Fig. 3 is a sectional elevation on the section line 3-3 of Fig. 1; Fig. 4 is an elevation of 45 the discharge mechanism partially in section along the line 4-4 of Fig. 1; Fig. 5 is a bottom plan view of the upper half of the distributing valve; Fig. 6 is a top plan 50 view of the lower half of the distributing valve; and Fig. 7 is an enlarged fragmentary sectional elevation of a bulb holder.

Referring to the drawings, the bed 10 carries the vertical bearing standard 11 55 through which passes the vertical shaft 12

fastened to the rotatable carrier frame 13. Near the outer periphery of the carrier frame 13 are disposed a series of rotatable holders 14 (eight are shown on the present machine) to which a miniature bulb 15 having a long 60 neck 16 is held by the balls 17 forced against the neck of the bulb by the springs 18. The holder 14 is grooved around the upper periphery so that it may be rotated at positions C and D by means of the belt 19. On 65 the lower end of the shaft 12 underneath the bed 10 is attached the gear 20 and the indexing plate 21.

A motor 22, through the pulleys 23 and the belt 24, drives the pulley 25 on one 70 end of the shaft 26 on the other end of which is the worm 27 which meshes with the worm gear 28 on the vertical shaft 29. Above the worm gear 28 is a pulley 30 which, through the belt 31, drives the pulley 32 on the lower 75 end of the vertical shaft 33 on whose upper end is fastened a pulley 34 to drive the belt 19 which runs over the idler pulley 35 so placed as to cause the belt to engage the groove in the holder 14 at positions C and 80 D as previously described. Near the periphery of the upper surface of the pulley 30 is placed a pin 36 whose upper end is held by a crank 37 on the vertical shaft 29 which has a disc 38 between the pulley and 85 the crank 37. The pin 36 engages a slot 39 in the plate 21 and causes the plate, and consequently the gear 20 and the carrier frame 13, to rotate through a small angle. The disc 38 is cut away at 40 to give clearance to the sides of the slot 39 and the indexing plate 21 is cut away at 41 between the slots 39 so as to receive the disc 38. 90

At position C is a gas torch 42 having a flat jet 43 to give a narrow horizontal flame 95 mounted on an L-shaped support 44 pivoted at the corner of the L to an arm 45 on the standard 46 mounted on the bed 10. A spring 47, attached to the end of the short arm of the L and to the rod 48 on the arm 49 of the standard 46, tends to keep the support 44 forced outward against the neck of the bulb. A gauge 50 attached to the top of the jet 43 maintains the proper distance between the jet and the neck of the bulb. An adjustable stop 51 on the arm 49 permits the amount of outward movement 100 of the support 44 to be adjusted. Gas and air are supplied through the tubes 52 and 53 to the valve 54 attached to the jet 43. 105 110

At position D is placed a sharpened chilling wheel 55 rotatably mounted on a support 56 attached to a Z-shaped spring standard 57 on the bed 10 so placed as to press the chilling wheel 55 against the neck of the bulb on the line of the heating previously described. The wheel 55 is moistened by water from a container 58 mounted on the standard 61 attached to the bed 10 through the regulating valve 59 and spout 60. The bulb neck rotating in this position causes the moistened wheel to rotate thus chilling the neck on the line of heating and so cracking the glass.

Between the positions D and E is a striking mechanism 62 (Fig. 2) which comprises a striker 63 attached to the end of a rotatable rod 64 having a spring 65 wound thereabout tending to turn the rod 64 in a direction opposite to the rotation of the carrier frame 13. The projection 66 acts as a stop for the inner end of the striker 63 causing it normally to assume a position perpendicular to the path of movement of the neck at this point. As the neck of the bulb passes the striking mechanism, the striker 63 hits the excess neck below the line of cracking and knocks it off to fall into a suitable receptacle. If the glass is not sufficiently cracked to permit the striker to knock off the excess neck, the striker is forced backward against the pressure of the spring 65 by the neck which is thus permitted to pass unbroken. Such bulbs may be run through the machine a second time.

At position F is placed a transfer mechanism to remove the bulb from the holder 14 and to deposit it in a slide 67 which conducts the bulb to a suitable container. The transfer device comprises a vertical tubular shaft 68 held in the bearing support 69 and having a gear 70 attached to its lower end driven by the gear 20 through the gear 70'. Through the tubular shaft 68 passes the tubular support 71 which has a bearing 72 at the upper end of the shaft 68. Below the bearing 72 is a ball bearing 73 against which presses a spring 74 whose other end presses against the collar 75 on the support 71 and exerts a downward pressure upon the support. A collar 76 attached to the support 71 just above the bearing 72 in the view of Fig. 4 supports the frame 77 which has four arms 78 each of which carries on its end an inverted cup 79 which contains a rubber cap 76' concave on its exposed end to fit over and engage the top of a lamp bulb and hold it by air suction as hereinafter described. Between the frame 77 and the cup 79 is a collapsible connector 80 around which is a spring 81 tending to keep the cup separated from the frame which permits the transfer mechanism to be adapted to differences in the bulb dimensions. An air passage 82, through the cap 76', connector 80, arm 78

and nipple 83 attached thereto on the top, and tube 84 attached to the nipple 83 at one end and to the nipple 85 on the lower half 86 of the distributing valve, communicates with the distributing valve. The lower 70 valve 86 is attached to the frame 77 so as to rotate therewith but free to move vertically. Springs 87 press the lower valve against the upper valve 88 which is attached to the upper end of the tubular support 71. The 75 valve 88 has an arc shaped trough 89 on its lower surface which communicates through the passage 90 with the passage 91 in the tubular support 71. The trough 89 extends between the nipple 85 for the position K and the nipple for the position L, communicating with the passage 82 at position K but just cut off from the passage for position L. The frame 77 is rotated by the rods 92 passing through holes in the arms of the frame and attached to the fork 93 fastened to the upper end of the shaft 68. The support 71 is raised and lowered by the action of the cam 94, fastened to the shaft 29 previously described, on the roller 95 on one end of a crank 96, pivoted at 97, whose other end is connected through links 98 to a block 99 fastened to the tubular support which is prevented from rotating by the pin 100 fastened in the block 99 and laterally restrained in an opening 101 in the crank 96.

Air suction is created by a pump 102, driven by the motor 22 previously described and, through the tube 103 connected to the lower end of the tubular support 71, is communicated to the passage 91 and, through the passage 90, trough 89 and passage 82, to the lamp bulb between positions K and L. The pump is cooled by water stored in a container 104 and connected to the pump by the tubes 105 and 106.

In operation, glass bulbs with excess necks are placed in the rotatable carrier frame at positions A and B. At position C, while the holder is being rotated the gas flame heats a narrow zone around the neck of the bulb and at position D while the holder is rotated, the moist wheel chills the neck around the heated zone causing the glass to crack. As the bulb moves from position D to position E, the excess neck hits against the striker and is knocked off falling into a convenient container. At F, the transfer mechanism attaches the bulb to it by suction and raises it, so as to clear the rotatable carrier frame as the latter moves the holder from F to G, and at the same time transfers it from position K of the transfer mechanism, which corresponds to position F of the rotatable carrier frame, to position L where the air suction is cut off releasing the bulb which drops into a suitable container. In positions G and H the holder is ordinarily empty although these positions may be used for loading positions.

What I claim as new and desire to secure by Letters Patent of the United States, is:—

1. In a machine for cutting glass, the combination of holders for incandescent lamp bulbs or similar articles, means for rotating said holders, a carrier for said holders, means for advancing said carrier step by step, means for heating a substantially narrow zone of the neck of said lamp bulb or similar article and means for subsequently chilling said zone.

2. In a machine for cutting glass, the combination of holders for incandescent lamp bulbs or similar articles, means for rotating said holders, a carrier for said holders, means for advancing said carrier step by step, means for heating a substantially narrow zone of the neck of said lamp bulb or similar article, means for subsequently chilling said zone and means for striking off the excess of said neck.

3. In a machine for cutting glass, the combination of a plurality of means for holding incandescent lamp bulbs or similar ar-

ticles with necks extending downwardly, 25 means for rotating said holding means, a carrier for said holding means, means for advancing said carrier step by step, means for heating a substantially narrow zone of the necks of lamp bulbs or similar articles 30 and means for subsequently chilling said zone.

4. In a machine for cutting glass, the combination of a plurality of means for holding incandescent lamp bulbs or similar articles with necks extending downwardly, 35 means for rotating said holding means, a carrier for said holding means, means for advancing said carrier step by step, means for heating a substantially narrow zone of 40 the necks of lamp bulbs or similar articles, means for subsequently chilling said zone and means for striking off the excess of the necks.

In witness whereof, I have hereunto set 45 my hand this 31st day of October, 1919.

CARL A. BROWN.
